Josef Fuchs.

UNITED STATES PATENT OFFICE.

JOSEF FUCHS, OF SCHWYZ, SWITZERLAND.

SHIP'S CABIN.

Application filed June 3, 1922. Serial No. 565,663.

To all whom it may concern:

Be it known that I, JOSEF FUCHS, a citizen of the Swiss Republic, residing at Schwyz, Switzerland, have invented certain 5 Improvements in Ships' Cabins, of which the following is a specification.

It has been proposed to make ship cabins in the form of buoyant boat-shaped bodies adapted to be assembled on a deck so that 10 they can be automatically detached from the ship in case of its sudden sinking, the boat cabins being provided with means of propulsion and steering.

The present invention relates to an arrangement of this kind and consists in so shaping the boat cabins that, when placed stern to stern and side to side on the ship's deck, the decks of the cabins combine into one continuous surface. This arrangement 15 has the advantage that a minimum space will be occupied by the cabins and that their combined decks can be utilized as a single deck without the employment of additional floors wherewith to span intervening spaces, as in previously known arrangements. The corner spaces formed by the straight walls inside and at the top of the cabins are divided off by curved partitions and utilized as watertight bulk heads 20 whereby the boat cabins are rendered unsinkable.

In the accompanying drawings,

Fig. 1 represents a diagrammatic end view of the ship showing the arrangement 25 of the cabins,

Fig. 2, a cross-section of the cabins on a larger scale and taken on the line A—A of Fig. 3, which is a side view of the cabin.

The cabins and berths for the passengers 30 and for the crew of a ship *a* are made in the form of water-tight, boat-shaped, buoyant bodies *b* each fitted with a keel *d*, with two propellers *o* and with a rudder *p*. The propellers are adapted to be driven in any 35 appropriate manner, and the rudder *p* is connected to a suitable gearing whereby it

can be operated from the interior of the boat. The floor *e* of each cabin is supported on beams *f*, a space being left between it and the bottom *c* of the boat for the reception of the machinery and for the storage of provisions and the like. The sides *g* of the boat are carried straight up to the deck *k*, and the corner space is divided off by curved walls *l* so as to form watertight bulk heads making the boat unsinkable. The boat is provided with port-holes *i* fitted with the usual hinged, tightly closing windows *h*. Entrance is effected 50 through the deck, by a manhole which is provided with a hinged lid *m* by which a watertight closure can be effected. Suitable stairs or ladders are provided whereby the occupants may enter and leave the cabins. 55

The cabin boats are arranged in juxtaposition, as shown in Fig. 2, on suitable supporting beams *n* on the deck of the ship. Two rows of cabins may be arranged, stern to stern, as shown in Fig. 1, space 60 being provided for the rudders to be turned back between the propellers. The cabins are preferably fixed to the supporting beams by means of fastenings which can be easily released from the interior of the cabins. 65 Thus, in case of a severe accident, and if there is no time to launch the cabin boats in the ordinary manner, they may be left to go down with the ship, the windows *h* and the lids *m* being closed and the boats 70 released so that the latter can remain on or regain the surface when the ship sinks. 75

I claim:—

Buoyant ship cabins in the form of decked boats shaped so that, when placed stern to 80 stern and side to side on a ship's deck, the decks of the boats combine into a continuous surface, the internal top corners of the boats being divided off by curved partitions so as to form watertight bulk heads. 85

JOSEF FUCHS.
